UNITED STATES PATENT OFFICE.

EDWARD WORTMANN, OF JERSEY CITY, NEW JERSEY.

KNOCKDOWN BARREL.

1,261,887.

Specification of Letters Patent.

Patented Apr. 9, 1918.

Application filed September 17, 1917. Serial No. 191,821.

To all whom it may concern:

Be it known that I, EDWARD WORTMANN, a citizen of the United States, residing at Jersey City, in the county of Hudson and State of New Jersey, have invented a new and Improved Knockdown Barrel, of which the following is a specification.

My invention has reference to improvements in collapsible or knock-down barrels made up of sections adapted to be compactly nested together for packing and shipping.

Primarily, my invention has for its purpose to provide an improved construction of barrel, of the general type stated, in which is embodied a peculiar arrangement or apron of staves having interlockable connection whereby to secure them against individual movement in the direction of their length, and flexible bands secured to the staves along their interlocking lines, whereby the said apron of staves and bands, as a single body may be quickly and conveniently bent to the round or barrel form.

My invention also has for its object to provide an apron of barrel staves joined by metal bands whose free ends have extended portions provided with interlockable elements brought into position when the barrel body is shaped up, for interlockably engaging each other and for receiving a suitable steel lock pin and by which the center portion of the body staves are maintained in a compact, strong and rigid relation.

A further object of my invention is the provision of an improved apron of assembled and interlocked set of barrel staves and including at least one metal band that takes around and is rigidly attached to each stave, as a hinged joint diametrically opposite the free or interlocking ends thereof, whereby the said apron of staves may be folded flatwise upon themselves with the barrel heads and other portions of the barrel structure held therebetween when the barrel is knocked down for being stored or shipped.

My present invention also embodies an improved means for securing and reinforcing the heads or chime ends of the barrel, in the nature of wooden hoops, each having an attached metal band, the ends of which have interlocking means designed for being worked by a suitable tool or implement, whereby to draw up the chime ends of the staves with their closing or head receiving

recesses brought into uniform horizontal alinement, and for effecting a positive and practical air tight connection of the staves and with the ends of the metal bands in position for being readily brought together for receiving a locking pin or steel member.

In its more subordinate features, my invention consists in the peculiar combination and arrangement of parts, all of which will be hereinafter explained, specifically pointed out in the appended claim and illustrated in the accompanying drawings, in which:

Figure 1 is a perspective view of a barrel embodying my invention, parts being in section and broken away.

Fig. 2 is a horizontal section of one end of the barrel, the abutting ends of the body staves being shown as brought together and ready for being finally drawn up and secured by the locking elements; the manner of applying the locking implement being also shown.

Fig. 3 is a fragmentary horizontal section, the meeting ends of the stave body being shown as brought to their final position and the locking elements assembled for receiving the lock pin or key.

Fig. 4 is a perspective view that illustrates the apron of staves, hereinafter referred to.

Fig. 5 is a cross section that shows the said apron folded over the barrel heads and the head clamping hoop and locking band.

Fig. 6 illustrates a supplemental or filler member hereinafter referred to.

Fig. 7 is a detail plan view of the chime end of a barrel with the filler member applied.

Fig. 8 is a perspective view of one of the wooden ends or binder hoops and a co-operating locking band.

Fig. 9 is a detail horizontal section taken on the line 9—9 on Fig. 1.

Fig. 10 is a detail section of an elevation of the lower end of the barrel.

In carrying out my invention, I provide a barrel body composed of a number of staves 1, each having at least one vertically extended and laterally projected extension 10 at one side and a corresponding vertical recess 11 at the other side.

In my construction, the staves that constitute the barrel body are arranged in the form of an apron with the recesses 11 of the series of staves that constitute the barrel body arranged for interlockably receiving

the extensions 10 of the adjacent staves, as is clearly shown in Fig. 4.

Steel strap bands 2 are nailed or otherwise secured to the set of staves and a pair 5 of the said bands 2 are applied to the staves along and over the upper and lower sets of interlocking edges, as is clearly shown in Fig. 1, and since the said bands are attached to the outer side of the staves, as shown, the 10 interlocking lines of the said staves are not visible when the barrel is set up, as shown in Fig. 1.

By providing staves with interlocking members, as stated, a barrel body of great 15 rigidity is provided without affecting the flexibility of the said body along the stave joints, and at the same time, it provides for holding the staves in absolute and uniform condition with their upper and lower crozing 20 or grooves 20 in perfect alinement when the staves that form the barrel body are drawn into barrel form; and furthermore, by connecting the series or apron of staves with each other and with their bands 2, as 25 shown and described, the staves can be almost instantly shaped up into the barrel body and ready for being locked to such position with the crozing or grooves 20 at each end held in perfect shape for receiving 30 the bevel edges of the barrel heads 4.

Each band 2 has its free ends extended to overlap each other, when the barrel staves are tightly drawn together, in the manner presently explained, and one of the said 35 ends has a fixedly held inwardly projected rivet-like lug 30 formed with an aperture 30^a and adapted for being pressed inwardly through an aperture 31 in the other end 32 of the band, the barrel stave over which the 40 said interlocking ends of the band meet being recessed as at α to provide for easily applying a seal wire or pin 33, as is clearly shown in Fig. 1.

After assembling the series of staves to 45 form the barrel body, a combined reinforce and binder hoop is applied to one end of the barrel. In my construction of knock-down barrel, the said reinforce or binder consists of a wooden hoop strip 5 to which is 50 fixedly attached, on the outside thereof, a metal strap band 6, the ends of which project beyond the hoop strip 5 to overlap each other when the hoop strip 5 is applied for interlockably engaging, as will presently 55 appear.

In applying the wooden and strap band hoop 5 and 6, it is extended around one end 60 of the barrel between strap metal guides 7 having upper and lower keepers 70—70, nailed or otherwise secured to some of the staves 1, and when carried around the said end of the barrel between the guides, as 65 stated, the said hoop and band members 5 and 6 are brought together in the manner clearly shown in Figs. 2 and 3, by reference

to which it will be seen, one of the ends of the band 6 has a horizontally elongated slot 50 and the other end has a round aperture 51 and the member that has the elongated slot 50 also has an inwardly projected fixedly held apertured rivet or stud 52 adapted for being pressed through the aperture 51 in the opposing end when the two ends are drawn over each other, which in practice is effected by a suitable implement 8 consisting of a handle and a rod 80, the latter being adapted for being pushed through the elongated slot 50 to engage with the aperture 51^a in the other or overlapped end, as is clearly shown in Fig. 2, it being understood that when the implement 8 has been thus applied by effecting a leverage pull in the direction of the arrow y in Fig. 2, the staves are drawn tightly together and the band ends are so overlapped that the lock 75 stud 52 is in position (see Fig. 2) for being pressed inwardly through the aperture 51 in the other end of the band and for receiving a locking or sealing pin 9, it being understood when the parts are thus positioned, the 80 implement 8 can be readily pulled away.

It will also be noticed, by referring to Figs. 1, 2, and 3, the band member 6, the opposite ends that extend beyond the ends of the wooden hoops 5 and the locking aperture 51 and locking studs 52, are relatively so arranged that when the parts are drawn together to lock the overlapping ends of the band 6, the adjacent ends of the wooden hoops 5 remain separated to form a vertical slotway 55 that extends the full width of the hoop and forms a recess into which the locking lug 52 is received, see Fig. 3, the said slotway 55 also forming a convenient guideway for entering the seal or locking wire 32 through the aperture of the locking lug 52.

Furthermore, by forming the adjacent ends of the wooden and metal hoops and bands 5 and 6, as stated and shown, the overlapping ends of the metal band present a substantially smooth finish and with the locking element so protected, that danger of the said locking element accidentally separating, (as would be the case if the said locking element was projected outside instead of inside the band ends and between the separated ends of the wooden hoop) is overcome.

Substantially the same protection for the seal or locking wire afforded by the arrangement of the connectible parts shown in Figs. 1, 2 and 3 is provided for the interlockable ends of the bands 2—2 by forming the outer face of the stave with recesses that extend vertically with respect to the said bands 2 to produce a recess at the back of the band 2 for receiving the apertured end of the locking bolt 30 and for passing the tie or locking wire down into the space α and through the aperture 38 in the said bolt, as shown.

After applying the first wooden hoop 5 and before locking the same, as stated, the head 4, at that end, is applied, its chamfered or beveled rim 40 readily slipping into and 5 interlockably engaging with the crozing of the barrel stave.

After the first head has been applied, as stated, the other head 4 may be readily applied to the other end of the barrel and secured by applying the hoop and band device 5 and 6, at that end, in the same manner that the band and hoop 5 and 6 were applied to the other. 10

After use, should the chime ends of the barrel tend to spread, a tight closure of the 15 meeting ends of the staves and for holding the stave ends tightly up to the chamfered edge of the heads, is effected by placing one or more fillers between the hoop 5 and the 20 chime end of the barrel, see Fig. 7.

The filler shown in detail Fig. 6 includes a wooden hoop strip 14 and a plurality of bendable metal strips 15 attached to the said strip 14 with the ends projected to turn 25 over the upper and lower edges of the hoop 5 to hold the filler in place, when the same is applied as shown in the aforesaid Fig. 7.

By reason of joining the staves that constitute the barrel body in an apron-like 30 shape, as stated, connecting each individual stave to the metal strap bands 2, formed of two parts hinged together as shown, when the barrel is knocked down for shipping 35 or storing, the stave formed apron will extend flatwise its length and by reason of the hinged connection of the band sections 3, the said apron can be folded back upon itself and over the heads 4 and the members 5 and 6 in such shape for being easily crated 40 in a manner that the parts that constitute the barrel may be shipped or stored in a substantial flatwise condition.

From the foregoing description taken in 45 connection with the drawings, the complete

construction and the manner in which the parts that constitute my improved barrel may be readily assembled and knocked down for packing will be readily understood. 50

It will be noticed in my construction of barrel, the staves are uniform in size and shape and by reason thereof in case any of the staves should break they may be easily replaced by others. 55

While for finish and stability, I have shown the upper and lower binders as composed of a wooden hoop 5 and a strap band 6, I do not restrict myself to making the end binders of wood and metal, as stated 60 and shown, since for some forms of barrels, the metal band 6 alone would suffice. 65

What I claim is:

In a barrel of the character stated and in which is included a body portion composed 65 of an apron of staves whose upper ends have crozing grooves and heads having chamfered rims for engaging the crozing grooves; of binders for the upper and lower ends of the barrel body, each binder consisting of a split wooden hoop and a metal band attached to the hoop, the said band having its ends extended beyond the wooden hoop ends, one end of the band having a 70 pulling slot and an apertured inwardly projected locking lug, the other end of the metal band having an aperture for the passage therethrough of the apertured locking plug, the said projected ends of the metal band, the wooden hoop and the locking 75 lug and the locking aperture being relatively so arranged, whereby when the binder is drawn tight, the meeting ends of the wooden hoop remain separated to form a vertical recess back of the metal hoop and 80 in line with the locking lug when moved into interlocked engagement whereby to provide for slipping a sealing wire through the inner projected end of the locking lug. 85

EDWARD WORTMANN.
